UNITED STATES PATENT OFFICE

158,020

SUN SHIELD

I. Martin Spier, New York, N. Y.

Application July 3, 1948, Serial No. 147,380

Term of patent 3½ years

(Cl. D57—1)

To all whom it may concern:

Be it known that I, I. Martin Spier, a citizen of the United States, residing at New York city, in the county of New York and State of New York, have invented a new, original, and ornamental Design for Sun Shield, of which following is a specification, reference being had to the accompanying drawing, forming part thereof.

In the drawing:

Fig. 1 is a front perspective view of a sun shield, showing my new design;

Fig. 2 is a horizontal sectional view through the forward portion of the sun shield as shown by line 2—2 in Fig. 1.

I claim:

The ornamental design for a sun shield, substantially as shown.

I. MARTIN SPIER.
